UNITED STATES PATENT OFFICE.

TYNDALL W. GROW, OF HOLLISTER, OKLAHOMA.

SHOE-LACE TIP.

Application filed December 22, 1923. Serial No. 682,283.

To all whom it may concern:

Be it known that I, TYNDALL W. GROW, a citizen of the United States, residing at Hollister, in the county of Tillman and State of 5 Oklahoma, have invented certain new and useful Improvements in a Shoe-Lace Tip, of which the following is a specification.

This invention appertains to shoe laces and more particularly to an improved tip 10 therefor.

The primary object of the present invention is the provision of an improved shoe lace tip, so constructed, that the same can be easily applied to a lace and engage the 15 lace in such a manner, that accidental displacement of the tip from the lace is reduced to a minimum.

Another prime object of the invention is the provision of a shoe lace tip embodying 20 a sheet metal body having teeth formed on its longitudinal edges adapted to bite into the lace, the body being formed of bendable material, so that the same can be folded about the lace to firmly clinch or grasp the 25 same.

A further object of the invention is to provide an improved shoe lace tip of the above character, which will be durable and efficient in use, one that will be simple and 30 easy to manufacture and one which can be placed upon the market and associated with a shoe lace at a small cost.

With these and other objects in view, the invention consists in the novel construction, 35 arrangement and formation of parts, as will be hereinafter more specifically described, claimed and illustrated in the accompanying drawings, in which drawings:

Figure 1 is a perspective view of the improved tip in operative position on a shoe lace.

Figure 2 is a plan view of the tip showing one step in the placing of the tip in position on a lace.

Figure 3 is a transverse section taken on the line 3—3 of Figure 2.

Figure 4 is a plan view of the blank from which the tip is constructed, and

Figure 5 is a detail section taken on the line 5—5 of Figure 1 showing the arrangement of the tip after the same has been applied to the lace.

Referring to the drawings in detail, wherein similar reference characters designate corresponding parts throughout the 55 several views, the letter A generally indicates the improved tip and B any preferred type of lace, with which the same can be associated.

The improved tip A comprises a flat sheet 60 metal body 10 of rectangular configuration having a plurality of saw teeth 11 formed on the longitudinal edges thereof.

In applying the tip to the lace B, the lace 65 B is laid on one face of the body 10, after which the longitudinal edges of the body are bent over and the teeth 11 forced into biting contact with the lace, as indicated by the reference character 12 as shown in Figures 2 and 3 of the drawings.

After the teeth 11 have been embedded 70 into the lace as indicated by the reference character 12, the body 10 is folded on the longitudinal central line as indicated by the reference character 13 so as to bring the 75 opposite teeth 11 into engagement with one another. This forms a substantial tubular casing with the teeth 11 disposed innermost in gripping contact with the lace.

It is obvious that after the lace tip A has 80 been folded as clearly shown in Figures 1 and 2 of the drawings, accidental displacement thereof from off of the lace B is practically impossible.

Changes in details may be made without 85 departing from the spirit or the scope of this invention.

What I claim as new is:

As a new article of manufacture, a tip 90 for shoe laces comprising a flat elongated metal body for engaging one face of a shoe lace, saw teeth formed on the longitudinal edges of the body and extending from one end thereof to the other adapted to be bent over the sides of the lace into intimate biting engagement with the opposite face of the lace from that engaged by the body, the body being adapted to be folded around the lace with the opposite teeth in engagement with one another.

In testimony whereof I affix my signature.

TYNDALL W. GROW.
